UNITED STATES PATENT OFFICE

111,136

DESIGN FOR A BATHTUB OVERFLOW SHIELD

Walter H. Ehrhorn, San Francisco, Calif.

Application April 11, 1938, Serial No. 76,436

Term of patent 3½ years

To all whom it may concern:

Be it known that I, Walter H. Ehrhorn, a citizen of the United States, residing in San Francisco, in the county of San Francisco and the State of California, have invented a new, original, and ornamental Design for a Bathtub Overflow Shield, of which the following is a specification, reference being had to the accompanying one sheet of drawings, forming part thereof.

I claim:

The ornamental design for a bathtub overflow shield, as shown.

WALTER H. EHRHORN.
